 tion of New York

Application December 4, 1937, Serial No. 178,131

14 Claims. (Cl. 22—2)

This invention relates to plate casting mechanism and more particularly to such mechanism wherein a closed mould is provided for casting plates under pressure and improved means is provided to force the molten metal into the mould.

In the use of closed moulds in plate casting, it is desirable that the molten metal be heated to the required temperature before forcing it into the mould, and that this temperature be maintained until the mould is completely filled. It is also desirable that the metal be maintained under constant pressure after being forced into the mould until it has solidified, and that excess metal be permitted to flow back from the mould. Provision to permit the escape of air and dross is also requisite.

One of the principal objects of this invention is to provide a plate casting mechanism embodying in its structure efficient and durable means whereby the above desiderata will be obtained.

Another object is to provide in a plate casting mechanism a closable electrically heated mould and an electrically driven pump operable to force molten metal into the mould.

Still another object is to provide means to maintain the molten metal under pressure in the mould until the same has solidified and then to permit excess molten metal to be automatically removed from the mould.

A further object is to provide a novel form of by-pass valve whereby the pressure on the metal will be constant until the same has solidified and by which the excess metal will be directed back to the melting pot.

A still further object is to provide a novel form of vent valve whereby air is permitted to escape from the spout, metallic dross will be trapped, and when the mould is filled this entrapped dross and excess metal will be released and flow back into the melting pot.

Another object is to provide a plate casting mechanism of generally improved construction, whereby the device will be simple, durable and inexpensive in construction, as well as convenient, practical, serviceable and efficient in its use.

With the foregoing and other objects in view, which will appear as the description proceeds, the invention resides in the combination and arrangement of parts, and in the details of construction hereinafter described and claimed.

The preferred embodiment of the invention is illustrated in the accompanying drawings, wherein:

Figure 1 is a side view of a plate casting mechanism embodying the features of this invention;

Figure 2 is a view similar to Figure 1, but with

the mould parts in section and showing these parts in closed mould position;

Figure 3 is an enlarged section through the intake portion of the mould and showing a valve controlled vent;

Figure 4, 5 and 6 are sectional views through a valve controlling the outlet flow of metal from a pump and showing the several positions of the parts thereof during its operation;

Figure 7 is an enlarged section through the intake portion of a somewhat modified form of valve controlled vent, dross trap, and excess metal release arrangement; and

Figure 8 is an electrical wiring diagram for the controls of the mould and pump operating motors.

The plate casting mechanism illustrated in the drawings is especially adapted to insure that the plates will be of uniform density throughout. While the casting mould shown is especially adapted for casting flat stereotype plates, it will be understood that the form of the mould may be altered for casting curved plates and still include the features of the invention. This mechanism is provided with closable mould parts, the interior of which is in connection with an electrically driven pump immersed in molten metal. The connecting spout between the pump and the mould is heated to prevent the metal from cooling as it flows therethrough. A vent is provided in the connecting spout to permit the escape of dross and air from the same and which is closable by means of an automatically pressure operated valve. An outlet valve is provided at the pump to control the flow of metal therefrom and to assist in maintaining constant pressure on the metal in the mould until it has solidified, and to permit excess metal to flow back to the melting pot when the pressure is relieved whereby no appreciable tail piece is left connected to the casting.

Referring now to Figures 1 and 2 of the drawings, a metal melting pot 11 in which a pump 12, preferably of the rotary gear type, is disposed, constitutes the receptacle in which the metal to be used is held and maintained in the proper molten condition. The pump 12 is supported within the pot 11 upon the end of a tubular member 13 through which the operative parts thereof are connected to an electric motor 14 by a shaft (not shown). The motor 14 is mounted upon a rear bracket or frame member 15 extending from one side of a standard 16.

The mould is constituted by upper and lower parts 17 and 18 respectively, the upper part 17 being pivoted between the bracket 15 and a similar front bracket or frame member 19 and the

lower part 18 being pivoted to the standard 16 in such a manner that the mould parts 17 and 18 are adapted to be swung together into closely engaging relationship. A hand lever 21 secured upon a shaft 22 to rock the same, actuates the mould parts 17 and 18 to swing them together, see Figure 2, or apart, see Figure 1, by means of an arm 23 secured to the shaft 22 and connected by a link 24 to the mould part 18, and an arm 25 secured to the shaft 22 and connected by a link 26 to the mould part 17. The end of the link 26 is connected to eccentric portion 27 on a shaft 28 journaled in a lug 29 on the mould part 17. When desired an electric motor 101 may be provided to drive a crank disc 102 which is drivingly connected to an arm 103 secured to the shaft 22 by a link 104. The crank disc 102 is mounted on a shaft 105 and is arranged to be driven by a pinion 106 secured on the shaft of the motor 101.

20 A lever 31, secured to the shaft 28, is connected by a link 32 to a hand lever 33 secured to a shaft 34 journaled in the brackets 15 and 19. The shaft 34 is formed with eccentric portions 35 on which the upper mould part is pivoted. A quadrant plate 36 formed as an extension of the bracket 15 is provided with spaced apart openings 37 through which a bolt 38 passes to secure the hand lever 33 and the shaft 35. The arrangement of the levers 31, 33, link 32, and eccentric portions of the shafts 28 and 34 is such that, when it is desired to cast plates of different thickness, the hand lever 33 is adjusted and clamped by the bolt 38 to the plate 36 in the proper position to locate the upper and lower mould parts 17 and 18 in position relatively to each other to tightly close upon a gauge frame 39 disposed between the mould parts and secured to the face 41 of the part 17. The gauge frame 39 may be interchanged with others in accordance with the thickness of the plate to be cast and is arranged to hold a matrix 42 against the face 41 of the mould part 17.

The mould part 17 is preferably hollow, the interior chamber 43 being connected with the face 41 by a plurality of openings 44 and with a suitable vacuum pump by a port 45, whereby the matrix 42 is maintained tightly against the face 41 due to the vacuum established in the chamber 43. The lower mould part 18 may have provision for holding a backing paper 46 upon the face 47 thereof, herein consisting of rolls 48 and a clamp plate 49. The part 18 is also hollow, the chamber 51 being in connection with a supply of cooling fluid by inlet and outlet ports 52 and 53. The usual valves (not shown) are provided to control the supply of cooling fluid to the mould part 18 to cool the casting after the same is made.

60 A spout or duct containing member 54 is secured to the standard 16 in position to have the outlet 55 of the duct 56 therein, correspond to the opening between the mould parts 17 and 18 when they are in closed position (see Figures 2 and 3). The spout 54 extends between the brackets 15 and 19 and has an upper surface 57 which the upper mould part 17 through the gauge frame 39 tightly engages, and a beveled surface 58 which the lower mould part 18 engages upon a correspondingly beveled surface 59. Closely adjacent the outlet of the duct 56, a vent 61 is provided. A pressure ball closing valve 62 is disposed in the vent 61 and which is normally retained in vent opening position by gravity. Molten metal under pressure flowing upwardly 70 through the duct 56 will cause the air therein

to escape out of the vent 61 and, until the pressure upon the ball 62 is sufficient to cause it to close the vent, metallic dross will escape therefrom. Suitable electrical heating units 64 are disposed in the walls of the spout 54 surrounding the duct 56 to insure that the molten metal is not cooled before it enters the mould and that it does not solidify with the cast plate.

The duct 56 is connected to the pump 12 by a conduit 65 through the open front end of a valve 10 cylinder 66, said open front end of the cylinder 66 constituting an inlet port. A valve plunger or piston head 67 is disposed in the cylinder 66. The plunger 67 has a rearwardly extending shank 68 guided by and through a cylinder end 69. The interior of the cylinder is in connection with the casing of the pump 12 at its open front end, or inlet port, the front wall 71 having a valve seat 72 formed therein to agree with the form on the adjacent end of the plunger 67. A spring 20 73 disposed in the cylinder 66 reacts against the piston head 67 and the cylinder end 69 to constantly urge the plunger forwardly into closed position upon the seat 72. The plunger 67 is acted upon by the pressure of the molten metal 25 from the pump 12 to unseat it and force it rearwardly against the urge of the spring 73 whereby it opens an outlet port 74 (see Figure 5), connected to the conduit 65 whereupon the metal flows through the latter into the duct 56 and 30 thence to the mould. When the mould and duct become completely filled with metal the increased pressure developed by the pump 12 causes the plunger 67 to retract further rearwardly against the action of the spring 73 and open a port 75 35 (see Figure 6), leading from the cylinder interior into the melting pot 11 whereupon excess metal escapes into the pot 11 and the pressure upon the metal in the duct and therefore upon the mould is maintained uniform and constant. The 40 term "port" as used herein is to be understood to define a part, or portion, of the cylinder 66 having a bore extending therethrough.

During the period that the mould is full and under pressure, cooling fluid is circulated through the chamber 51 in the lower mould part 18 and as soon as the casting metal has solidified, the pump 12 is stopped and the plunger 67 seats on the valve seat 72 closing the opening into the pump. Unsolidified metal still remaining in the conduit 65 and duct 56, flows downwardly, through the port 74, through the cylinder 66 in back of the piston head 67 and into the pot 11 through the port 75, thus clearing from the solidified cast plate in the cooled mould, substantially all excess metal. By maintaining the metal in the mould under constant and uniform pressure, a plate is cast which is substantially of uniform density throughout. The provision of the novel by-pass valve whereby the excess 60 metal is drained from the spout, saves, not only metal, but time in removing surplus metal from the cast plate.

The arrangement shown in Figure 7 permits the escape of air from the duct leading to the mould and includes means to entrap metallic dross and to insure its escape with excess metal after the mould is filled, while maintaining the metal in the mould under a constant pressure. The spout or duct containing member 81, illustrated in Figure 7, is secured to the standard 16 in position to have the outlet 82 of the duct 83 therein, correspond to the opening between the mould parts 17 and 18 when they are in closed position as shown. The spout 81 extends between 75

the brackets 15 and 19 and has an upper surface 84 which the gauge frame 39 tightly engages, and a beveled surface 85 which the lower mould part 18 engages upon the corresponding beveled surface 59.

Closely adjacent the outlet 82 the spout 81 is provided with an upwardly extending cavity 86 from which a port 87 extends to the surface 84. Another port 88 is provided in the spout 81 extending from the surface 84 adjacent the port 87 into connection with a duct 89, which is directed rearwardly with its mouth 91 overlying the melting pot 11. A casing 92 having a recess 93, which extends over both the ports 87 and 88 to connect the same, is mounted upon the surface 84 of the spout 81. The casing 92 is provided with a bore 94 which is in alignment with the port 87 and in which a valve member 95 is slidably mounted. The valve member 95 is adapted to close the port 87, being constantly urged against the surface 84 by a spring 96 reacting against the member 95 and a plug 97 threadingly mounted in the upper portion of the bore 94 and by which the tension on the spring 96 may be adjusted. The spring 96 is disposed about a stem 98 provided upon the valve member 95 and which is slidably mounted in the plug 97. The valve member 95 is provided with a vent groove 99 which, when the valve member is in port closing position, connects the port 87 with the duct 89 through the recess 93 and port 88.

By the provision of the vent groove 99, air is permitted to escape from the duct 89 through the port 87, and metallic dross collects and is entrapped in the cavity 86 insuring that only clean metal will be forced into the mould. After the mould is filled, the increased pressure built up by the continued action of the pump 12 will force the dross against the valve member 95 raising it, by compressing the spring 96, to open the port 87 whereby the dross and excess metal will escape through the ports 87 and 88 into the duct 89 and thence to the melting pot 11 while a constant pressure will be maintained on the metal in the mould as it is being cooled. By this arrangement, the valve cylinder 66, with its associated parts, may be omitted and the plate casting mechanism of this invention will be further simplified without affecting its efficiency.

When the mould operating motor 101 is used to open and close the mould by means of the crank disc 102, the arm 103 and the link 104, it may be electrically interlocked with the pump motor 14 in accordance with the control circuits shown in Figure 8. As herein shown, the action of the motors 14 and 101 is substantially automatic for the cycle of operations in the casting of a plate. The operation is started by pressing a normally open push button 107 to close a circuit (to a switch controlling solenoid 111) that may be traced from a main line conductor 108, by conductor 109 to one terminal of the push button 107, thence from the other terminal of the push button 107 through conductor 112, to one terminal of an interlock switch 113, the other terminal of the switch 113 being connected by a conductor 114 to one terminal of the solenoid 111. The other terminal of the solenoid 111 is connected by a conductor 115 to the other main line conductor 116.

The solenoid 111 thus energized closes a circuit between the terminals of a switch 117, one of which is connected to the conductor 109 by a conductor 118 and the other being connected to one terminal of the mould motor 101 by a con-

ductor 119. The other terminal of the motor 101 is connected by a conductor 121 to the main line conductor 116. Energization of the motor 101 rotates the crank disc 102 to close the mould. Connected to the shaft 105 of the crank disc 102 are two switch controlling cam discs 122 and 123. The cam disc 122 by means of cams 124 and 125 control a switch 126, one terminal of which is connected by a conductor 127 to the conductor 109, and the other terminal is connected by a conductor 128 to the terminal of the solenoid 111 to which the push button 107 is connected. As soon as the motor 101 starts, the cam 124 releases the switch 126 to close the circuit, whereby the solenoid 111 is maintained energized until the mould is closed, whereupon the cam 125 opens the switch 126 and the motor 101 stops.

As soon as the mould is closed and the motor 101 is stopped, a cam 129, provided on the cam disc 123 closes a switch 130 to complete a circuit 20 through a conductor 132 from the conductor 109 and through a conductor 131 to one terminal of a motor 133 of a suitable timing controller, the other terminal of which motor is connected by a conductor 134 to the main line conductor 116. 25 The motor 133 through reduction gears 135 rotates a pair of switch controlling cam discs 136 and 137 mounted on the shaft 138. The cam disc 136 is provided with a cam surface 139 adapted to close a switch 141 and to maintain it closed a 30 predetermined interval of time to energize a switch controlling solenoid 142. The switch 141 has one of its terminals connected by a conductor 143 to the main line conductor 108 and its other terminal connected to one terminal of the 35 solenoid 142 by a conductor 144. The other terminal of the solenoid 142 is connected by a conductor 145 to the main line conductor 116 through the conductor 118.

When energized, the solenoid 142 closes a circuit between the terminals of a switch 146, one of which is connected to the conductor 145 and the other of which is connected by a conductor 147 to a terminal of the pump motor 14. The other terminal of the motor 14 is connected by 45 a conductor 148 to the main line conductor 108 through the conductor 109. Energization of the motor 14 actuates the pump to fill the closed mould with casting metal and this operation continues until the camming surface 139 passes 50 the switch 141 which then opens to de-energize the solenoid 142 whereupon the switch 146 is opened and the motor 14 stops.

The solenoid 142 also controls the interlock switch 113 which is in closed position when the 55 solenoid 142 is de-energized and open when the solenoid is energized, and the switch 146, controlling the pump motor, is closed. The switch 113 is in the circuit of a switch 149 controlled by a cam lug 151 on the cam disc 137. The cam 60 lug 151 is disposed to close the switch 149 after a short interval of time has elapsed after the pump has stopped, so as to permit cooling of the metal in the mould before it can be opened. One terminal of the switch 149 is connected to 65 one terminal of the switch 113 through the conductor 112 by a conductor 152, the other terminal of the switch 113 being connected by a conductor 114 to the conductor 128 connected to one terminal of the switch 126. The other terminal of 70 the switch 149 is connected by conductors 153 and 143 to the main line conductor 108. Upon closing of the switch 149, the solenoid 111 is energized to start the mould motor 101 to open the mould and this operation is continued after 75

the cam 151 passes the switch 149, and allows it to reopen, due to the cam lug 125 permitting release of the switch 126 to maintain the solenoid 111 energized until the cam lug 124 again opens the switch 126.

5 The action of the switch 149 is similar to the action of the push button 107 in that it is only in operation a sufficient amount of time to insure the closing of the switch 126. The motor 133 is maintained energized a sufficient length of time to insure the opening of the switch 149 by the release of the same from the action of the lug 151, and also to set the timing motor 133 in position for its next starting operation, to close 10 the switch 141 by the continued action of the cam 129. The interlock switch 113 prevents the possible operation of the motor 101 to open the mould, while the pump motor 14 is operating. From the above, it will be obvious that a control 15 system is provided for the motors 14 and 101 whereby the casting operation may be substantially automatic, requiring only the attention of the operator to initially start it by means of the push button 107.

25 The various cam discs 123, 124 and 136, 137 are arranged to provide the proper time intervals for the successive operations. For instance, the switch 126 maintains the motor 101 energized until the mould is closed, the cam 129 then starts 30 the timing motor 133 and maintains it energized until the metal in the mould is cooled and the cam discs 136 and 137 are reset in their start position. The disc 136 maintains the pump motor 14 energized a length of time sufficient to 35 fill the mould with metal, and the disc 137 closes the mould motor circuit to start opening of the mould and holds it closed until the switch 126 closes the maintaining circuit for the motor.

It will be understood that the invention may 40 be embodied in other specific forms without departing from the spirit or essential attributes thereof, and it is therefore desired that the present embodiment be considered in all respects as 45 illustrative and not restrictive, and it will be further understood that each and every novel feature and combination present in or possessed by the mechanism herein disclosed forms a part of the invention included in this application.

What I claim is:

50 1. A valve for use in a plate casting mechanism to control the flow of metal to the plate mould thereof, including a hollow casing having an inlet port in one end, a first outlet port spaced from the inlet port end of the casing and at one side thereof, and a second outlet port spaced from the first outlet port and further away from the inlet port end of the casing and at the other side thereof, a valve plunger having an inlet port closing end slidably mounted in the casing 55 and being of proper length to open the first outlet port into communication through the casing with the second outlet port when in position to close the inlet port, and a spring acting on the plunger to normally hold it in inlet port closing position, the plunger being movable in the casing by pressure imposed against its inlet closing end, to open said inlet port and the first outlet port into communication through the 60 casing.

65 70 2. A valve for use in a plate casting mechanism to control the flow of metal to the plate mould thereof, including a hollow casing having a series of three ports spaced apart lengthwise thereof, a spring pressed plunger slidable in the

75 casing and normally closing the first of the said ports and being of such length as to partly open the second of the ports into communication with the third of the ports through the casing when the plunger closes the first port, the length of the plunger being sufficient to block communication between the second and third ports when the plunger is moved away from the first port to open it and the second port into communication through the casing, the plunger being movable further in the casing to open the third port into communication through the casing with the first and second ports.

80 3. In a stereotype plate casting machine, the combination with a molten metal supply and a mold, of a conduit communicating the mold with the molten metal supply, a member having a dross receiving cavity formed therein and communicating with the conduit and the atmosphere adjacent the mold, a valve movable responsive to molten metal pressure for interrupting communication between the vent cavity and the atmosphere, and means for forcing molten metal under pressure through the conduit into the mold to fill it, the metal dross and air escaping 85 through the vent cavity until the valve is moved to interrupt communication between the vent cavity and the atmosphere by continuation of said molten metal pressure after the mold is filled.

90 4. In a stereotype plate casting machine, the combination with a molten metal supply and a mold, of a conduit communicating the mold with the molten metal supply, a member having a dross receiving vent cavity formed therein and communicating with the conduit and the atmosphere adjacent the mold, a valve normally closed to interrupt communication between the vent cavity and the atmosphere and movable to open position responsive to molten metal pressure, and means for forcing molten metal under pressure from the metal supply through the conduit into the mold, the force of the molten metal opening the valve whereby air is forced through the vent cavity to the atmosphere and metal dross and excess metal are discharged from said cavity.

95 5. In a stereotype plate casting machine, the combination with a molten metal supply and a mold, of a conduit communicating the mold with the molten metal supply, a member having a dross receiving vent cavity communicating with the conduit adjacent the mold, a return duct communicable with the said cavity and leading therefrom to a location to discharge to the atmosphere and into the molten metal supply, a valve normally biased to closed position to interrupt communication between the vent cavity and the return duct and movable to open position responsive to molten metal pressure, and means 100 for forcing molten metal under pressure from the metal supply through the conduit into the mold, the force of the molten metal opening the valve whereby air is forced to the atmosphere and metal dross and excess metal are discharged 105 through the vent cavity and return duct back to the molten metal supply.

110 6. In a stereotype plate casting machine, the combination with a molten metal supply and a mold, of a conduit communicating the mold with the molten metal supply, a member having a dross receiving vent cavity communicating with the conduit adjacent the mold, a return duct communicable with the said cavity and leading therefrom to a location to discharge to the at- 115

mosphere and into the molten metal supply, a valve normally biased to closed position to interrupt communication between the vent cavity and the return duct and movable to open position responsive to molten metal pressure, a groove formed in the valve to constantly communicate the vent cavity with the atmosphere, and means for forcing molten metal under pressure from the metal supply through the conduit 5 into the mold, the force of the molten metal initially forcing air through the vent groove to the atmosphere and finally opening the valve whereby metal dross and excess metal are discharged through the cavity and return duct back 10 to the molten metal supply.

7. In a stereotype plate casting machine, a first movable mold member and a second movable mold member, a pivotal support for each mold member on which it may be swung to open 15 the mold, a supporting member pivotally secured to each mold member at a point spaced from the said pivotal support whereby it may be moved to open and close the mold, the pivotal support and spaced supporting member for one mold member being provided with eccentrically 20 movable components operably secured to the said mold member whereby the space between the first and second mold members may be varied by the movement of the said movable 25 components to cast plates of different thickness between the mold members, means for operably connecting the eccentrically movable components for simultaneously adjusting them so that the first and second mold members remain in parallelism during the said adjustment, and means to secure the eccentric components in any selected 30 position.

8. In a stereotype plate casting machine, a molten metal supply, a mold having separate 35 mold members, means for pivotally supporting each mold member for independent swinging movement toward and away from the other mold member, a fixed member having a conduit communicating with the molten metal supply, means 40 for moving the mold members about their pivots to and from engagement with the fixed member, mold engaging surfaces formed on the fixed member, a surface formed on each mold member to engage a mold engaging surface of the fixed 45 member when the mold members are moved to engagement with each other and the fixed member whereby the separate mold members and fixed member form a mold cavity with which the conduit communicates, and means for forcing molten metal from the molten metal supply through the conduit into the mold cavity.

9. In a stereotype plate casting machine, the combination with a molten metal supply and a mold, of a valve casing communicable with the 50 metal supply to receive molten metal within the casing, a conduit communicable with the valve casing and mold, a valve movable within and accurately engaging the casing to vary the metal-receiving space within the casing and to 55 control communication through the casing between the metal supply and the conduit, the valve being biased to continuously oppose the flow of molten metal from the supply into the casing to thereby exert constant pressure on the 60 metal, means for forcing molten metal under pressure from the metal supply into the casing, the force of the molten metal moving the valve against its bias to increase the volume of molten metal within the valve casing and to establish 65 communication between the metal supply and 70

the conduit so that metal flows under pressure into the mold to fill it and to produce pressure therein.

10. In a stereotype plate casting machine, the combination with a molten metal supply and a mold, of a valve casing communicable with the metal supply, a conduit communicable with the valve casing and mold, a valve movable within the casing to control communication through the casing between the metal supply and the conduit, 10 the valve being biased to oppose the flow of molten metal from the supply into the casing to thereby exert constant pressure on the metal, a return port formed in the casing and communicable with the metal supply and controlled 15 by said biased valve, means for forcing molten metal under pressure from the metal supply into the casing, the force of the molten metal moving the valve against its bias to establish communication between the metal supply and the conduit so that metal flows under pressure into the mold to fill it, and the continued flow of the metal from the supply after the mold is filled moving the biased valve further into the valve casing against its bias to open the return port so that 20 excess metal is returned therethrough to the metal supply.

11. In a stereotype plate casting machine, the combination with a molten metal supply and a mold, of a valve casing communicable with the metal supply, a conduit communicable with the valve casing and mold, a valve movable within the casing to control communication through the casing between the metal supply and the conduit, 30 the valve being biased to oppose the flow of molten metal from the supply into the casing to thereby exert constant pressure on the metal, a return port formed in the casing and communicable with the metal supply and controlled 35 by said biased valve, means for forcing molten metal under pressure from the metal supply into the casing, the force of the molten metal moving the valve against its bias to establish communication between the metal supply and the conduit so that metal flows into the mold to fill it, and the continued flow of the metal from the supply after the mold is filled moving the biased valve further into the valve casing against its bias to open the return port so that excess metal is returned therethrough to the metal supply, the 40 biased valve returning responsive to the said stress to its initial position when the said metal force is discontinued thereby establishing communication between the conduit and the metal supply through the return port to drain metal 45 from the conduit back into the metal supply.

12. In a stereotype plate casting machine, the combination with a molten metal supply and a mold, of a valve casing communicable with the metal supply, a conduit communicable with the valve casing and mold and with the atmosphere at a location adjacent the mold, a normally open vent valve movable responsive to molten metal pressure for interrupting the communication between the conduit and the atmosphere, a valve 60 movable within the casing to control communication between the metal supply and the conduit and biased to oppose the flow of metal from the supply into the casing, a metal return port formed in the casing and controlled by said 65 biased valve, means for forcing molten metal under pressure from the metal supply into the valve casing, the force of the molten metal moving the biased valve against its bias to establish communication between the molten metal supply and 70

the conduit so that metal flows into the mold to fill it, the initial flow of the metal towards the mold forcing air past the vent valve to the atmosphere until the mold is filled and then continued flow of the metal from the supply moving the biased valve further into the casing against its bias to open the return port so that excess metal is returned therethrough to the metal supply.

13. In a stereotype plate casting machine, the combination with a molten metal supply and a mold, of a valve casing communicable with the metal supply to receive molten metal within the casing, a conduit communicable with the valve casing and mold, a return duct communicable with the conduit and leading therefrom to a location to discharge into the molten metal supply, a normally closed yieldable discharge valve for controlling communication between the conduit and the return duct, a valve movable within and accurately engaging the casing to vary the metal-receiving space within the casing and to control communication between the metal supply and the conduit, the valve being biased to continuously oppose the flow of molten metal from the supply into the casing to thereby exert continuous pressure on the metal, means for forcing molten metal under pressure from the metal supply into the valve casing, the force of the metal moving the valve against its bias to in-

crease the volume of molten metal received within the casing and to establish communication between the metal supply and the conduit so that metal flows into the mold to fill it and produce pressure therein, the force of the metal opening the discharge valve to discharge excess metal through the return duct back to the metal supply.

14. In a stereotype plate casting machine, a mold having separate mold members, one mold member being pivotally mounted for swinging movement relative to the other to open and close the mold, supports for the mold members, spaced rotatable members operably supported by the supports, a connecting component supported by and movable with each rotatable member and disposed in eccentric relation therewith, each connecting component being rotatably secured to a mold member so that rotative movement of the rotatable member imparts movement to the mold member, and means for operably connecting the spaced rotatable members so that rotative movement of one rotatable member simultaneously imparts rotative movement of like amplitude to the other to thereby adjustably move one mold member towards and away from the other in parallelism therewith so that plates of different thickness may be cast between the separate mold sections.
